UNITED STATES PATENT OFFICE.

PLINY K. WESTCOTT, OF BROOKLYN, NEW YORK, ASSIGNOR TO MARY A. KENNEY, OF BROOKLYN, NEW YORK.

VEHICLE LANDING APPARATUS.

Application filed August 8, 1923. Serial No. 656,313.

To all whom it may concern:

Be it known that I, PLINY K. WESTCOTT, a citizen of the United States, a resident of Brooklyn, in the county of Kings and State 5 of New York, have invented certain new and useful Improvements in Vehicle Landing Apparatus, of which the following is a specification.

The invention relates to a landing structure for aerial vehicles such as airplanes and hydroplanes, which is designed to bring the vehicle to rest within narrow space limitations, and the primary object of the invention is to provide an apparatus of the 15 above nature wherein the surface of the apparatus which engages the vehicle as the latter passes thereover, is of such a nature as to retard the motion of the vehicle efficiently. It will be understood that the features of the invention may be used alone or 20 in combination with additional mechanism for checking the speed of the vehicle.

Further objects and advantages of the invention will be in part obvious and in part 25 specifically pointed out in the description hereinafter contained, which, taken in connection with the accompanying drawings, discloses a preferred embodiment thereof. Such embodiment, however, is to be considered as merely illustrative of its principles.

In the drawings—

Figure 1 is a side view of a landing apparatus constructed in accordance with the invention,

Figure 2 is a transverse section taken along the line 2—2 of Figure 1 looking in the direction of the arrow.

In accordance with the present invention the runway over which the vehicle passes 40 in landing is provided with stop members positioned to be engaged and moved by the vehicle as it passes along the apparatus and such stop members are yieldingly urged toward the position out of which the vehicle 45 tends to move them; thus as the vehicle passes along its motion is retarded by the work it performs in displacing the stop members and the latter subsequently return automatically to their initial position. 50 Preferably the stop members are also arranged to give the effect of an inclined plane

over which the vehicle must pass in landing as will be later described in greater detail.

Under some conditions a landing apparatus may be employed in which the speed 55 of the vehicle is retarded solely by stop members as above described or such members may be employed in conjunction with other speed retarding means, for example, as described in United States Patent No. 60 1,437,236, issued to me on November 28, 1922.

The invention is illustrated as applied to a landing apparatus having one or more continuous traveling webs of the nature disclosed in Figure 2 of the above patent. As shown the web consists of a plurality of transverse slats 1 supported by a chain 2 running over sprocket wheels 3 and 4. As the detailed construction of the above parts 70 is not essential they will not be described in greater detail; in fact, the invention may be used as well with stationary runways, if desired.

In the present embodiment of the invention the stop members above mentioned comprise a plurality of inverted U-shaped rods or cables 5 which may swing angularly about shafts 6 supported in suitable bearings 7 on the slats 1. The stop members 5 80 are urged toward an upper or elevated position in which they most tend to retard the motion of the vehicle, for example, by means of heavy coil springs 8 acting between the hubs 9 of the stop members and 85 screw collars 10 which are threaded onto the shafts 6. Suitable stops 11 will also be provided to limit the extent to which stop members 5 may be turned upwardly by 90 springs 8.

Thus when a downwardly projecting part of a vehicle, such as the wheel illustrated in Figure 1, passes over the stop members 5 the members directly underneath the wheel will have been fully depressed while the 95 stop members directly in front of the wheel oppose its progress, thus the motion of the vehicle is retarded due to the force necessary to move the stop members as aforesaid. Furthermore the stop members directly 100 ahead of the wheel constitute, in effect, an inclined plane up which the vehicle tends

to climb as it passes along, also tending to retard its speed.

While a specific embodiment of my invention is being disclosed it will be obvious 5 that many changes may be made therein without departing from its principles as defined in the appended claims.

I claim:

1. A vehicle landing apparatus comprising 10 a runway having stop members mounted above the same in position to engage and retard the motion of a vehicle passing thereover, supporting means for such members permitting the same to move to non-retarding 15 position when engaged by a vehicle, and means yieldingly urging said members towards their vehicle retarding position whereby the vehicle moves the members to non-retarding position against the resistance 20 of said last-mentioned means.

2. A vehicle landing apparatus comprising 25 a runway having transverse stop members mounted above the same in position to engage and retard the motion of a vehicle passing thereover, supporting means for such members permitting the same to assume elevated and depressed positions and means yieldingly urging said members toward their elevated positions whereby the

vehicle moves the members to depressed position against the resistance of said last-mentioned means.

3. The combination set forth in claim 2 wherein said stop members are pivoted on axes extending transversely of the runway 35 and springs are provided tending to urge said stop members toward an upright position.

4. A vehicle landing apparatus comprising 40 a continuously traveling web having transverse slats thereon and stop members movably mounted above said slats in position to retard the motion of the vehicle passing thereover, and means yieldingly urging said stop members toward their vehicle 45 retarding position.

5. A vehicle landing apparatus comprising 50 a runway, and stop members disposed along said runway, comprising transverse rods disposed above the runway and pivoted to swing toward the latter, together with springs urging said rods toward an upright position.

In testimony that I claim the foregoing, I have hereunto set my hand this 27th day 55 of July, 1923.

PLINY K. WESTCOTT.
